LOOP ANTENNA TUNING CIRCUIT

William J. Stolze, Astoria, N. Y., assignor to Radio Corporation of America, a corporation of Delaware

Application October 23, 1948, Serial No. 56,188

6 Claims. (Cl. 250—20)

1

This invention relates to signal selecting circuits for radio receivers and particularly to a permeability-tuned loop antenna circuit.

A loop antenna for a broadcast receiver is conventionally associated with a variable capacitor-tuned circuit. However, a capacitor-tuned circuit used in connection with a loop antenna has a number of disadvantages. Thus, in order to obtain the desired tuning range, the variable capacitor must have a large capacitance at the low frequency end of the tuning range, with the result that the total impedance of the tuned circuit at that frequency is low. This, in turn, reduces the sensitivity of the antenna circuit at the low frequency end of the tuning range, and the signal-to-noise ratio is poor. Another disadvantage of a capacitor-tuned antenna circuit is the unpleasant acoustic feedback howl which may be caused by vibration of the capacitor plates.

These disadvantages of prior antenna circuits for radio receivers can be overcome if a loop antenna is associated with a permeability-tuned circuit. A permeability-tuned circuit has the advantage of compactness and light weight, and furthermore the circuit can be mounted in any part of the receiver chassis. Excellent performance has been secured in the past with capacitive electromagnetic wave antennae such as a rod type antenna in conjunction with a permeability-tuned circuit. However, a rod antenna is unsuitable for broadcast receivers in view of its detrimental body capacitance effects, its low sensitivity in shielded buildings and the unsightly appearance of a rod extending beyond the cabinet. For these reasons, an inductive electromagnetic wave antenna such as a loop antenna is preferred in the broadcast receiver field.

Unfortunately, the sensitivity of a loop antenna coupled to a conventional permeability-tuned circuit is very low. Even the best previously known permeability-tuned loop antenna circuits have sensitivities that are low compared to that of a variable capacitor-tuned circuit. Thus, a conventional input circuit for a radio receiver comprises a loop antenna connected in series with an inductor, the inductance of which may be varied by the movement of a paramagnetic core, and a capacitor connected across both the loop antenna and the inductor. The sensitivity of this circuit is low because the inductance of the inductor must be sufficiently large at the low frequency end of the tuning range so that the entire broadcast range can be covered by a variation of the inductance of the inductor which will, in turn, alter the effective inductance of the input cir-

2

cuit. Accordingly, the inductance of the loop antenna must be made small which results in a reduced pickup of the electromagnetic wave energy and thus explains the low sensitivity of this circuit.

It has been suggested in the patent to Cutting, 2,285,766, to shunt the inductor of the circuit associated with a capacitive antenna by a capacitor, and to tune the inductor and capacitor to 10 the image frequency thereby to obtain an image suppression circuit. It is well known that the image frequency is equal to the frequency of the desired wave plus or minus twice the intermediate frequency depending upon the frequency relation of the local oscillator and the incoming signal. A circuit as disclosed by Cutting, however, will not improve the sensitivity of a permeability-tuned antenna circuit.

It is the principal object of the present invention, therefore, to provide a permeability-tuned loop antenna circuit having a tuning range sufficient to cover the broadcast band and which has a good sensitivity.

A further object of the invention is to provide 25 a simple and inexpensive input circuit for an electromagnetic wave transmission channel of the type including an inductive pickup device and an inductor variable by a paramagnetic core which will cover the broadcast range and which 30 will have a sensitivity which is of the order of that which can be obtained with a variable capacitor-tuned loop antenna circuit.

An input circuit for a wave transmission channel in accordance with the present invention 35 comprises a loop antenna, a parallel resonant circuit and a capacitor connected across the series combination of the loop antenna and the resonant circuit. The parallel resonant circuit consists of an additional fixed capacitor and a variable inductor including a paramagnetic core movable to 40 vary the resonant frequency of the input circuit over a predetermined frequency range. A paramagnetic material is defined as a material having a magnetic permeability greater than that of a 45 vacuum, which is unity. The magnetic permeability of a paramagnetic material may be independent of the magnetizing force or it may vary with the magnetizing force, in which case the material is called ferromagnetic.

In accordance with the present invention, the 50 circuit constants of the resonant circuit are chosen so that its resonant frequency falls between the image frequency and the resonant frequency of the input circuit for any position of 55 the tuning core. Consequently, the reactance of

the resonant circuit is purely inductive at any resonant frequency of the input circuit. Since the portion of the inductive reactance contributed by the capacitor will vary in magnitude over the tuning range, the effective inductance variation of the input circuit is greatly increased.

The novel features that are considered characteristic of this invention are set forth with particularity in the appended claims. The invention itself, however, both as to its organization and method of operation, as well as additional objects and advantages thereof, will best be understood from the following description when read in connection with the accompanying drawing, in which:

Fig. 1 is a circuit diagram of a radio receiver input circuit embodying the present invention;

Fig. 2 is the equivalent circuit of the input circuit of Fig. 1;

Figs. 3 and 4 are graphs referred to in explaining the operation of the input circuit of the invention; and

Fig. 5 shows a curve illustrating the relative response of the circuit of Fig. 1 over the broadcast frequency range.

Referring now to Fig. 1, there is illustrated an input circuit 8 for a wave transmission channel such as a radio receiver comprising an inductive electromagnetic wave antenna 1 which may be a loop antenna as shown. Inductor 2 is connected to one terminal of loop antenna 1, and the series combination of loop antenna 1 and inductor 2 is shunted by capacitor 3. Inductor 2 includes paramagnetic core 4 which may, for example, consist of powdered iron mixed with a suitable binder and compressed to the desired shape. Alternatively, paramagnetic core 4 may consist of a ferrite which is a ferromagnetic material. A ferrite consists of a mixture of the oxides of various bivalent metals with ferric oxide Fe_2O_3 . Core 4 is movable as indicated by arrow 5 with respect to inductor 2 to vary the inductance of the inductor.

In accordance with the present invention, capacitor 6 is connected across inductor 2, and its function and operation will be explained hereinafter. Inductor 2 and capacitor 6 thus form a parallel resonant circuit 7. Antenna input circuit 8 accordingly consists of loop antenna 1, parallel resonant circuit 7 and capacitor 3. Antenna input circuit 8 may be connected, for example, to radio-frequency amplifier 10, as shown, or to a converter or mixer tube if desired. Thus, control grid 11 of amplifier 10 is connected to the junction point of parallel resonant circuit 7 and capacitor 3. Cathode 12 of amplifier 10 is connected to ground, that is, to the other terminal of loop antenna 1 and to one terminal of capacitor 3 through resistor 13 bypassed by capacitor 14. Anode 15 is connected to tuned circuit 16, the inductor 17 of which may be tuned by paramagnetic core 18 which preferably is moved in unison with core 4 as indicated at 20. Tuned circuit 16 is connected to a suitable positive voltage source indicated at +B through resistor 21 bypassed to ground through capacitor 22. The amplified radio-frequency signal may be derived across output inductor 23 as shown. It is to be understood that the local oscillator of the receiver may also be tuned by a paramagnetic core which preferably is moved in unison with cores 4 and 18.

In accordance with the present invention, parallel resonant circuit 7 is tuned to a frequency which is above the frequency of the wave to be

received and appreciably below the image frequency. Consequently, the reactance of parallel resonant circuit 7 is purely inductive at the resonant frequency of input circuit 8 which, of course, is tuned to the frequency of the wave to be received. This may be more clearly understood by reference to Fig. 3 where the reactance of inductor 2 with respect to frequency is illustrated by dotted curve 26. Curve 27 of Fig. 3 illustrates the reactance of parallel resonant circuit 7 with respect to frequency. In Fig. 3 X_L indicates the inductive reactance and X_C the capacitance reactance, while f_1 is the resonant frequency of parallel resonant circuit 7 for a particular position of core 4. It is well known that the reactance of a parallel resonant circuit below its resonant frequency f_1 is inductive and changes to a capacitive reactance at a frequency above resonance. At the resonant frequency of the circuit, the reactance becomes zero as shown by curve 27.

Consequently, for any wave having a frequency below f_1 , the resonant frequency of parallel resonant circuit 7, the reactive impedance of the circuit is purely inductive, and its value depends upon how far the frequency of the wave is removed from f_1 . In accordance with this invention, the circuit constants of parallel resonant circuit 7, that is, the capacitance of capacitor 6 and the inductance of inductor 2, are chosen so that the resonant frequency of parallel resonant circuit 7 is always above the frequency of the wave to be received which equals the resonant frequency of input circuit 8, and furthermore, so that f_1 is always below the image frequency.

At the high frequency end of the tuning range, core 4 is fully withdrawn from inductor 2 so that its inductance is at a minimum. In that case, the resonant frequency of input circuit 8, indicated at f_8' , is comparatively far removed from the resonant frequency f_1 of parallel resonant circuit 7. Accordingly, the reactive impedance of parallel resonant circuit 7 at the frequency f_8' is slightly higher (curve 27) than the inductance of inductor 2 indicated by curve 26. On the other hand, when core 4 is fully within inductor 2, its inductance is at a maximum and the resonant frequency of input circuit 8 is at the low end of the frequency range. The inductive reactance of inductor 2 is now shown by curve 30 of Fig. 4, while curve 31 illustrates the reactance of parallel resonant circuit 7. In this case, the resonant frequency of input circuit 8 is indicated by f_8'' and it will be seen that f_8'' is closer to the resonant frequency f_2 of parallel resonant circuit 7 than it was under the conditions illustrated in Fig. 3.

This is due to the fact that the resonant frequency of parallel resonant circuit 7 varies over a larger range with a movement of core 4 than does the resonant frequency of input circuit 8. Accordingly, the effective inductance of parallel resonant circuit 7 is varied over a larger range by the provision of capacitor 6 than would be possible if the inductance change were due only to movement of core 4.

The equivalent circuit of input circuit 8 is illustrated in Fig. 2 where 7' represents schematically a variable inductor which is equivalent to capacitor 6 and inductor 2. The effective inductance variation of inductor 2 is increased by capacitor 6. In a representative circuit embodying the present invention the inductance of loop antenna 1 may amount to .2 millihenries and the

inductance of inductor 2 may be variable by movement of core 4 between .1 and 1.2 millihenries. The capacitance of capacitor 6 may amount to 60 micromicrofarads and that of capacitor 3 may amount to 30 micromicrofarads.

It will therefore be seen that the variation in inductance of inductor 2 caused by movement of core 4 is 12 to 1. However, the effective variation in inductance of parallel resonant circuit 7 at the resonant frequency of input circuit 8 caused by movement of core 4 is increased to 17 to 1. The resonant frequency of parallel resonant circuit 7 at the lower end of the broadcast range, that is, at 560 kilocycles, amounts to 590 kilocycles. At the high frequency end of the broadcast range, that is, at 1600 kilocycles, the resonant frequency of parallel resonant circuit 7 amounts to 2,050 kilocycles with the circuit constants given above. For an intermediate frequency of 455 kilocycles, the image frequency is 910 kilocycles above the frequency of the wave to be received. Hence, at the low frequency end of the broadcast range, the image frequency is 1,470 kilocycles and at the upper end of the broadcast range, the image frequency amounts to 2,510 kilocycles. It will accordingly be seen that the resonant frequency of parallel resonant circuit 7 is substantially less than the image frequency. Figs. 3 and 4 clearly show that if the resonant frequency of circuit 7 would approach the image frequency, the inductive reactance of circuit 7 would not be increased by the provision of capacitor 6.

Capacitor 3 may be adjustable, that is, it may be a trimmer capacitor which may be used to adjust the frequency of input circuit 8 at the high frequency end of the tuning range, that is, when core 4 is fully removed from inductor 2. Capacitor 6 may also be a trimmer capacitor and adjustment of its capacitance will control the tuning range of input circuit 8.

The relative response of input circuit 8 over the broadcast frequency range is illustrated by curve 35 of Fig. 5. A response of 100 corresponds to that of a variable capacitor-tuned antenna circuit with the same loop antenna 1. It will be seen that the average sensitivity of the circuit of the invention is well above 60 per cent of that of a variable capacitor-tuned antenna circuit.

There has thus been described a radio receiver input circuit of the type comprising a loop antenna connected in series with an inductor including a paramagnetic core for varying its inductance. The inductor is shunted by a capacitor, and the resonant frequency of the thus obtained parallel resonant circuit is always above the frequency of the wave to be received and below the image frequency. Since the resonant frequency of the parallel resonant circuit is varied by movement of the core at a different rate than that of the entire input circuit, the variation of the effective inductance of the input circuit is substantially increased so that the entire broadcast range can be covered with a good sensitivity. The circuit of the invention is very simple and inexpensive, and its performance is comparable to the best conventional antenna circuits.

What is claimed is:

1. An input circuit for a radio receiver comprising a loop antenna, a parallel resonant circuit and a first capacitor, said first capacitor being connected across said antenna and said resonant circuit arranged in series, said resonant circuit consisting of a second capacitor and a variable inductor, said inductor including para-

magnetic core means movable to vary the resonant frequency of said input circuit over a predetermined frequency range, the circuit constants of said resonant circuit being chosen so that its resonant frequency falls between the image frequency and the resonant frequency of said input circuit for any position of said core means, whereby the reactance of said resonant circuit is inductive at any resonant frequency of said input circuit and is larger than the inductance of said inductor.

2. An input circuit for a wave transmission channel comprising an inductive electromagnetic wave antenna, a parallel resonant circuit and a first capacitor, said first capacitor being connected across the series combination of said antenna and said resonant circuit, said resonant circuit consisting of a second capacitor and an inductor, said inductor including paramagnetic core means movable to vary simultaneously the resonant frequency of said input circuit over a predetermined frequency range and the resonant frequency of said resonant circuit over a different frequency range, the circuit constants of said resonant circuit being chosen so that its resonant frequency falls between the image frequency and the resonant frequency of said input circuit for any position of said core means, whereby the reactance of said resonant circuit is purely inductive at any resonant frequency of said input circuit and is larger than the inductance of said inductor.

3. An input circuit for a radio receiver comprising a loop antenna, a parallel resonant circuit and a first fixed capacitor, said first capacitor being connected across said antenna and said resonant circuit arranged in series, said resonant circuit consisting of a second fixed capacitor and a variable inductor, said inductor including a paramagnetic core movable to vary the resonant frequency of said input circuit over a predetermined frequency range, the circuit constants of said resonant circuit being chosen so that its resonant frequency is always below the image frequency and is closer to the resonant frequency of said input circuit when said inductor has its maximum value than when said inductor has its minimum value, whereby the reactance of said resonant circuit is always inductive at any resonant frequency of said input circuit and is larger than the inductance of said inductor.

4. An input circuit for a radio receiver comprising an inductive electromagnetic pick-up device, a parallel resonant circuit and a first capacitor, said first capacitor being connected across the series combination of said device and said resonant circuit, said resonant circuit consisting of a second capacitor and a variable inductor, said inductor including a paramagnetic core movable to vary the resonant frequency of said input circuit over a predetermined frequency range, the circuit constants of said resonant circuit having values so that purely inductive reactance is presented to waves of the resonant frequency of said input circuit, which reactance is larger at the low frequency end of said range than at the high frequency end thereof and is always larger than the inductance of said inductor, and the resonant frequency of said resonant circuit is always below the image frequency.

5. An input circuit for a radio receiver comprising a loop antenna, a variable inductor and a first capacitor, said first capacitor being con-

ected across said antenna and said inductor arranged in series, said inductor including paramagnetic core means movable to vary the resonant frequency of said input circuit over a predetermined frequency range, and additional means for increasing the effective inductance variation of said inductor consisting of a second fixed capacitor connected across said inductor and having such a capacitance that the reactance of said inductor and second capacitor at the resonant frequency of said input circuit is purely inductive and substantially larger at the low frequency end of said range than at the high frequency end thereof, the resonant frequency of said inductor and second capacitor being always 15 below the image frequency.

6. An input circuit for a radio receiver comprising a loop antenna, a parallel resonant circuit variably tunable to a frequency below the image frequency and above the frequency of the 20 wave to be received, and a first fixed capacitor, said first capacitor being connected across said antenna and said resonant circuit arranged in series, said resonant circuit consisting of a second fixed capacitor and a variable tuning inductor, said inductor including paramagnetic core means movable to vary the resonant frequency of 25

said input circuit over a predetermined frequency range, the variation in inductance of said inductor caused by movement of said core means being larger than 10 to 1, the capacitance of said second capacitor having a value such that the reactance of said resonant circuit at the resonant frequency of said input circuit is purely inductive and larger at the low frequency end of said range than at the high frequency end thereof and is always larger than the inductance of said inductor, whereby the effective variation in inductance of said resonant circuit caused by movement of said core means is larger than 15 to 1.
